UNITED STATES PATENT OFFICE.

JOHN M. FISCHER, OF DE SOTO, MISSOURI.

WHIFFLETREE-HOOK.

1,112,777.

Specification of Letters Patent.

Patented Oct. 6, 1914.

Application filed April 21, 1914. Serial No. 833,473.

To all whom it may concern:

Be it known that I, JOHN M. FISCHER, a citizen of the United States, residing at De Soto, in the county of Jefferson and State of Missouri, have invented certain new and useful Improvements in Whiffletree-Hooks, of which the following is a specification.

My invention relates to whiffle tree hooks and more particularly to a device attached 10 to a whiffle tree for removably holding a trace thereon.

The primary object of my invention is to provide an improved means for mounting a trace fastener on a whiffle tree.

Another object of my invention is to provide 15 an improved means for mounting the elastic element for removably holding the guarding member in position.

A further object of my invention is to provide 20 an improved ferrule being cast in one piece and having a means formed thereon for receiving the elastic element and the trace.

A still further object of my invention is to provide 25 an improved device of the character described that is simple in construction, efficient in operation and one that can be manufactured and placed on the market at a minimum cost.

Other objects as well as the nature, characteristic features and scope of my invention will be more readily understood from 30 the following description taken in connection with the accompanying drawings and pointed out in the claims forming a part of this specification.

Referring to the drawings:—Figure 1 is a top plan view of my invention; Fig. 2 is a longitudinal sectional view taken on the line 40 2—2 of Fig. 1 in the direction in which the arrow points; Fig. 3 is a top plan view of my improved ferrule applied to a portion of the whiffle tree.

Referring more particularly to the drawings in which similar reference numerals 45 designate corresponding parts throughout the different views I provide a whiffle tree 1 having a reduced end 2, the latter having mounted thereon by means of rivets 3 and 4 my improved ferrule 5.

The ferrule has the outer end thereof reduced to form a substantially flat neck 6, the outer edge of which has formed thereon an enlarged head 7 which has one end thereof tapered as at 8 to facilitate the mounting 50 of a trace 9 thereon and is further pro-

vided with an opening 10 extending therethrough for a purpose to be hereinafter described. Extending laterally from diametrically opposite points and formed integral with the outer surface of the ferrule 5 at points approximately intermediate the ends of the ferrule are studs 11 which have pivotally mounted thereabout a yoke 12.

The yoke 12 is formed preferably of resilient material and has its outer ends thereof slightly enlarged and provided with openings 13 for removable engagement with the studs 11. Rigidly secured to the under surface of the yoke approximately intermediate the ends of the same by means of a suitable fastening device, preferably a rivet 14, is a lever 15, the outer end of which is curved slightly upward as at 16 to form a substantial finger piece for a purpose to be hereinafter referred to and is provided adjacent the outer edge thereof with an opening 17 in which is mounted the reduced end 70 of a guarding pin 18. The guarding pin 18 depends from the lever and has its lower reduced end removably engaged in the opening 10 for retaining the trace 9 upon the neck 6.

For the purpose of holding the pin 18 in engagement with the opening 10, I have provided the upper surface of the ferrule 5 about the opening in which the pin 4 is engaged with a longitudinal recess 10 which is slightly slanted toward the outer end of the ferrule and has secured in the same by 80 means of the pin 4 a leaf spring 20, the free end of which extends upwardly and is slidably engaged in the longitudinal recess 21 in the opposite end of the lever 15 which forms a handle member for facilitating the 90 operation of the pin 18. The recess 21 being directly above the spring 20 cooperates with the spring and prevents any lateral movement of the lever 15 and greatly facilitates the operation of the pin 18 within the 100 opening 10.

The operation of my device is as follows: When it is desired to place the trace 9 upon the neck 6 all that is necessary to do is for the user to place one hand (not shown) upon the inner or handle portion of the lever 15 and press the same downwardly against the tension of the spring 20 and thus remove the pin 18 from engagement with the opening 10 in the head 7. The opening in the trace is then placed about the tapered portion 110 8 of the head and slid into position

upon the neck 6. The handle portion of the lever 15 is then released and the spring 20 causes the pin 18 to again engage the opening 10. To remove the trace from position on the neck it is obvious that this operation need only be reversed. If it is desired to remove the trace with one hand all that is necessary is for the user to place one of his thumbs (not shown) upon the under surface of the curved portion 16 of the lever 15 and press the same upwardly. This causes the handle portion of the lever 21 to bear against and press the spring downwardly. It can be easily seen that the user while holding the forward end of the lever in an upward position the trace 9 can easily be removed by the fingers of the hand which he is using to hold the forward end in this position.

From the above description taken in connection with the accompanying drawings it can be easily seen that I may form the yoke 12, the lever 15 and the pin 18 in one piece in order to reduce the cost of manufacture, however, the form shown is the preferred form. The reason for this is because in the case that only certain parts should become broken, these parts could be obtained at a very low price and readily connected to the original parts.

I desire it to be understood that great stress be laid upon the manner in which the spring 20 is mounted. The pin 4 by which the spring is secured serves the dual purpose of securing the spring to the ferrule in place on the end of the whiffle tree. Again, the free end of the spring co-acting with the recess 2 in the handle portion of the lever tends to maintain the pin 18 in a position directly above the opening 10 and greatly facilitates the operation of the device.

From the above description taken in connection with the accompanying drawings it can be easily seen that I have provided a device that is simple in construction containing but a few simple parts that can be easily and cheaply manufactured and when manufactured can be placed on the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention,

what I claim as new and desire to secure by Letters Patent is:—

1. In a whiffle tree hook, the combination with a ferrule having a neck and a head formed thereon, and a yoke pivotally connected to the ferrule, a lever secured intermediate its ends to said yoke, a guarding pin depending from the forward end of the lever, the rear end of the lever constituting a handle and having the under surface thereof provided with a longitudinal recess, a leaf spring carried by the ferrule the free end of the spring bearing against the recess in the handle portion of the lever for maintaining the pin in a position above the head.

2. In a whiffle tree hook, the combination with a ferrule having a neck and a head formed thereon, said head having an opening, studs projecting from the opposite sides of the ferrule, of a spring yoke detachably connected about the studs, a lever carried by the yoke, a guarding pin depending from the forward end of the lever for removable engagement with the opening, the rear end of the lever constituting a handle portion and having its under surface provided with a longitudinal recess, a leaf spring, one end of said spring being secured to the ferrule, and the opposite end of the spring bearing against the longitudinal recess in the handle portion of the lever for maintaining the pin in engagement with the opening and preventing lateral movement of the same.

3. In a whiffle tree hook, the combination with a ferrule having a neck and a head formed thereon, said head having an opening, said ferrule further provided with a longitudinal groove adjacent the free end thereof, and means for fastening the ferrule to the whiffle tree, of a lever pivotally connected to the ferrule, a guarding pin carried by the forward end of the lever for engagement with the opening in the head, the rear portion of the lever having its under surface provided with a longitudinal recess, a leaf spring disposed in the recess in the ferrule and secured by the fastening means of the ferrule, the free end of the spring bearing against and slidably arranged within the recess in the lever for maintaining the pin in engagement with the opening and for preventing lateral movement of the parts.

In testimony whereof I affix my signature in presence of two witnesses.

JOHN M. FISCHER.
